UNITED STATES PATENT OFFICE.

JAMES HENRY WOODS, OF LUMBER, ARKANSAS.

VALVE-GEAR.

SPECIFICATION forming part of Letters Patent No. 617,383, dated January 10, 1899.

Application filed March 7, 1898. Serial No. 672,911. (No model.)

To all whom it may concern:

Be it known that I, JAMES HENRY WOODS, a citizen of the United States, residing at Lumber, in the county of Columbia and State 5 of Arkansas, have invented a new and useful Valve-Gear, of which the following is a specification.

My invention relates to valve-gears particularly adapted for locomotive-engines, the 10 object in view being to provide a valve motion whereby the connections may be arranged compactly to adapt the same for use in connection with locomotive-engines having short valve-stems.

15 A further object of the invention is to provide such a combination and arrangement of parts for communicating motion to the valve-stem as to provide for giving the valve any desired length of stroke irrespective of the 20 length of the valve-stem or the space in which the valve-gear must be disposed.

25 A further object of the invention is to provide simple and efficient means in connection with the valve-gear for reversing the engine, the means whereby this reversal is accomplished being exposed to facilitate access thereto.

30 Further objects and advantages of this invention will appear in the following description, and the novel features thereof will be particularly pointed out in the appended claim.

35 In the drawings, Figure 1 is a view of a valve-gear constructed in accordance with my invention. Fig. 2 is a plan view of the same as shown when applied to a double or locomotive engine.

Similar numerals of reference indicate corresponding parts in both figures of the drawings.

40 My invention contemplates the construction of a valve-gear comprising the minimum number of parts and so arranged relatively to the parts of the engine as to occupy the 45 minimum space without interfering with the communication of a stroke of the required length to the valve, and as it is in locomotive-engines that the greatest difficulty is experienced in providing a compact reversing- 50 valve gear I have deemed it advisable to show the mechanism embodying the essential

features of my invention applied to such an engine, wherein 1 designates the valve-chest; 2, the cylinder; 3, a driving or other wheel axle, (which may be arranged either in front or in rear of the valve-chest, so far as the merits of my invention are affected thereby,) and 4 an eccentric for actuating a connecting-rod 5.

The connecting-rod in the improved construction serves as a means for communicating motion to a cranked rock-shaft 6, having an inner crank 7, arranged in any suitable position to suit the direction of the application of power by the connecting-rod, and having an outer crank 8 for communicating motion to a valve-stem. Obviously this mechanism should be duplicated at the opposite side of the engine to suit the double construction thereof, the inner crank serving as a means whereby motion may be communicated 65 to the rocker from any suitable rotary shaft or axle of the engine, whether that shaft is located in front or in rear or above or below the rocker.

The valve-stem is of sectional construction, 70 and comprises a member 9, which I will term a "rocker" member and which is terminally connected to the outer crank-arm 8 of the rock-shaft, and a member 10, which I will term a "valve" member and which is connected at its remote end with the valve for controlling the admission and exhaust of motive agent. The contiguous extremities of these valve-stem members are connected by means of a link 11, pivotally mounted at an 75 intermediate point, as shown at 12, said stem members having pivotal connection with the link, and one of them, as the valve member 80 10, having a sliding or adjustable connection with the link to vary the interval between its point of connection and the fulcrum-point 85 of the link and also enable said pivotal point of connection to be arranged upon either side of the fulcrum of the link to reverse the engine, it being obvious that the motion of the 90 valve when the connection is above the fulcrum will be the opposite of that which will be imparted to the valve when the point of connection is below the fulcrum.

The structure thus far described is such as 100 to be practically independent of any considerable distance between the rock-shaft and

- the valve-chest, for the reason that the rocker member of the valve-stem may be connected with the link at any desired distance from the fulcrum thereof to give the required throw 5 to the link, and hence to the valve member of the stem, and the adjustment of the extremity of the valve member with relation to the link to communicate the desired throw to the valve with a given throw of the link.
- 10 may be accomplished by any suitable means, such as a reversing-lever 13, mounted upon a standard 14 and terminally connected by a rod 15 with the block 16, which is fitted to slide in the slot 17 of the link. Any suitable 15 means may be employed for holding the reversing-lever in the desired position to maintain the slide at the required point in the slot of the link.
- From the above description it will be seen 20 that the rock-shaft, which forms an intermediate member of the connections between the cam-shaft and the valve-stem, enables me to use a short valve-stem irrespective of the position of the eccentric, and yet obtain any 25 desired throw of the steam-valve. Also by this arrangement the link, which is arranged at an intermediate point of the valve-stem, (being used in direct connection with the valve-stem instead of in connection with a 30 connecting-rod, as in the ordinary construc-

tion,) is exposed exteriorly of the engine, where it is accessible to the engineer.

Various changes in the form, proportion, and the minor details of construction may be resorted to without departing from the spirit 35 or sacrificing any of the advantages of this invention.

Having described my invention, what I claim is—

In a reversing-valve gear, the combination 40 of a rock-shaft having oppositely-extending terminal crank-arms, means operatively connected with one of the crank-arms for imparting movement to the rock-shaft, a slotted link disposed between the engine-cylinder and 45 rock-shaft, a rocker member connecting the other crank-arm of the rock-shaft with the link, a block slidably mounted in the slotted link, a valve member connecting said block with the valve, and means for shifting the 50 block and holding it in an adjusted position, substantially as described.

In testimony that I claim the foregoing as my own I have hereto affixed my signature in the presence of two witnesses.

JAMES HENRY WOODS.
